UNITED STATES PATENT OFFICE.

BENJAMIN F. MANNES, OF CHIPPEWA FALLS, WISCONSIN.

DESIGN FOR A FONT OF TYPE.

57,536.

Specification for Design.

Patented Apr. 12, 1921.

Application filed June 30, 1919. Serial No. 307,874. Term of patent 14 years.

To all whom it may concern:

Be it known that I, BENJAMIN F. MANNES, a citizen of the United States, residing at Chippewa Falls, in the county of Chippewa Falls and State of Wisconsin, have invented a new, original, and ornamental Design for a Font of Type to be Used in Printing Lines, of which the following is a specification, reference being had to the accompanying drawing, forming part thereof.

The figure is a plan view of a font of type for use in printing lines, showing my new design.

I claim:

The ornamental design for a font of type for use in printing lines, as shown.

BENJAMIN F. MANNES.
